UNITED STATES PATENT OFFICE

DAVID H. ZELL, OF BROOKLYN, NEW YORK

VANITY CASE

Application filed October 24, 1928. Serial No. 314,553.

This invention relates to vanity cases, and has for its primary object to provide a vanity case which is simple and inexpensive in its construction and in which a novel means is incorporated for securely holding and completely protecting a lipstick or similar cosmetic for easy accessibility and without necessitating the opening of the case.

It is a more particular object of my invention to provide a vanity case in the general form of a book and having a hinged cover or closure together with means confined against the case body at the hinged end of said cover for removably receiving a lipstick holder and from which said holder may be laterally withdrawn at one side edge of the case.

It is another feature of my invention to provide a common ornamental flexible covering material such as imitation leather for the cover and body wall of the case and for a tubular receiver for the lipstick holder and said covering material constituting the sole means which retains said tubular member in associated relation with the case body. When the case is closed said tubular member is held by said covering material in the plane of the case body, while upon the opening of the hinged cover or closure for the case, said tubular member is permitted to assume a slight angular relation relative to the plane of the case body. This construction thus permits of a very close arrangement of the tubular receiver for the lipstick holder with respect to the hinge of the cover or lid for the case and the movement of said cover or lid to its full open position.

It is a further general object of my invention to provide a vanity case of the above character, the several parts of which are of relatively simple construction and compactly arranged so that the article will present a neat and attractive appearance, and will occupy a minimum of space in a purse or handbag.

With the above and other objects in view, the invention consists in the improved vanity case, and in the form and construction of its several parts as will be hereinafter more fully described, illustrated in the accompanying

drawings, and subsequently incorporated in the subjoined claims.

In the drawings, wherein I have illustrated one simple and practical embodiment of the invention, and in which similar reference characters designate corresponding parts throughout the several views,—

Figure 1 is a perspective view showing the general form and appearance of a vanity case embodying my present improvements;

Fig. 2 is a top plan view, the cover or lid of the case being in open position;

Fig. 3 is an enlarged longitudinal section taken on the line 3—3 of Fig. 1 and showing the cover in partly open position;

Fig. 4 is a fragmentary horizontal sectional view taken on the line 4—4 of Fig. 3;

Fig. 5 is a plan view similar to Fig. 2, the powder receptacle or container and the latch cover plate being removed;

Fig. 6 is a sectional view on an enlarged scale taken on the line 6—6 of Fig. 5;

Fig. 7 is a detail perspective view of the lipstick holder, and

Fig. 8 is a similar view of the powder container.

Referring in detail to the drawings, 5 designates the body plate of the case. Upon one side of this body plate a relatively thin sheet metal frame 6 is arranged, said frame having marginal flanges 7 constituting side and end walls for the case body, one of said end flanges and the opposite side flanges being inwardly spaced from the corresponding edges of the body plate 5. For the purpose of conveniently and rigidly connecting the plate 5 and the frame 6 with each other, tongues 8 are struck from the body plate 5 and bent outwardly and clinched upon the inwardly extending flanges of the frame 6 which are disposed in parallel relation to the plate 5.

One of the end flanges 7 of the frame 6 is provided centrally of its upper edge with a hinged knuckle 9 with which similar hinged knuckles 11 on one end of a cover frame 10 are aligned to receive a hinge pintle 12. The frame 10 is secured upon one side of the cover plate 13 by means of tongues 14 struck from said plate in a similar manner to the attachment of the frame 6 to the body plate 5 as 130

above described. The frame 10 is provided with relatively narrow flanges 15 extending along its opposite side edges and one of its end edges in spaced relation to the corresponding edges of the plate 13. The end flange 15 is centrally provided with a keeper lug 16 adapted to engage a resilient latch element indicated at 17 of any preferred type arranged within one end of the frame 6 and 10 suitably attached to one wall thereof. This latch element may be actuated by a suitably formed finger piece 18 projecting outwardly through an opening in the end flange 7 of the frame. An angular sheet metal strip indicated at 19 is suitably secured within the end of the frame 6 and covers the greater portion of the latch member 17, the covering flange of said strip having a central opening as shown at 20 in Fig. 2 of the drawings, through which 20 the keeper lug 16 may extend when the cover of the case is closed.

Within the body of the case between the angular metal strip 19 and the flange 7 upon which the cover of the case is hinged a powder container or receptacle 21 is adapted to be arranged. Each of the side flanges 7 of the frame 5 is provided with a slight indentation indicated at 22 forming an internal protrusion which coacts with one of the side flanges 23 of the container 21 to securely hold the same in place. The corresponding side flanges of the cover frame 10 are also indented as at 23 providing external recesses which accommodate the internal protrusions formed by the 25 indentations 22 on the flanges 7 when the cover of the case is closed.

It will be noted that the body plate 5 and the cover plate 13 in contour simulate the two covers of a book, the flange 7 upon which the plate 13 is hinged supporting representing the back or binding of the book. In accordance with my present invention, for the purpose of receiving and retaining a lipstick holder in convenient association with the case structure, I provide a tubular member 24 preferably of sheet metal and rectangular in cross sectional form. This tubular member extends substantially across the entire width of the case and one end thereof is closed as 40 clearly shown in Fig. 4 of the drawings. This member is arranged with one side thereof in close contact with the flange 7 of the body frame to which the cover is hinged, but is not secured or fixed to said flange. To the opposite 45 longitudinal side wall of the member 24, a rigid strip of steel 25 is secured, as by means of the tongue 26 struck from said strip and extending through an opening in the wall of the member 24 and clinched thereon as seen 50 in Fig. 4 of the drawings. The strip 25 is of a length equivalent to the width of the body and cover plates 5 and 13 of the case.

The member 24 is held in associated relation with the body of the case by means of 55 the flexible covering material 27. This ma-

terial may be of leather or any other suitable material which may be embossed or provided with suitable surface ornamentation to impart a pleasing or attractive appearance to the article. As herein shown, this covering 70 is in the form of a continuous single sheet of the material, extending over and entirely covering the outer surfaces of the plates 5 and 13 and around the member 24 and the end strip 25. The material is drawn or tensioned 75 closely upon the parts and the edges thereof are turned inwardly, certain of said edge portions extending between the cover plates 5 and 13 and the frames 6 and 10 respectively, as clearly seen in Fig. 3 of the drawings and 80 between which the edges of the material are clampingly confined and held. As shown in Fig. 4, other edge portions of the covering material extend between the opposite ends of the metal strip 25 and the outer side wall of 85 the member 24.

The lipstick holder 28 as shown in detail in Fig. 7 may be of conventional form and consists of a rectangular metal tube open at one end and having a slot 29 in one side wall 90 thereof to receive the finger piece or stud 30 of a slidible member 31 arranged within said tube 28 and in which one end of the lipstick indicated at 32 is fitted. To the other end of the holder 28 a small loop or finger piece 33 is pivotally attached. The opposite side walls of the member 24 at the open end thereof are suitably notched or recessed as indicated at 34 to receive the projecting finger piece or button 30 when the lipstick holder 100 is inserted within the tubular member 24.

To the inner side of the lid or cover of the case, a mirror is preferably attached. As herein shown, this mirror may consist of a chromium plated steel plate 35 of proper 105 shape or form so that it may be closely fitted within the flanges 15 of the cover frame. The protrusions formed by the indentations 23 of the side flanges 15 fit into notches or recesses 110 in the side edges of the mirror plate and provide additional means of security therefor.

From the foregoing description considered in connection with the accompanying drawings, the construction and relative arrangement of the several parts of my improved vanity case will be clearly and fully 115 understood.

When the case is closed, it presents the novel and attractive appearance of a small book, the lipstick holder being entirely contained within the tubular member 24 and the pivoted finger piece 33 thereof lying between the marginal edges of the cover and body plates of the case which project laterally beyond the frame flanges 7. Thus, not only is the cosmetic itself completely protected, but the holder in which it is contained is quite inconspicuous though at all times accessible so that it may be instantly withdrawn from the tubular member 24 and used without ne- 120 125 130

cessitating the opening of the case itself. It will therefore, be appreciated that an article of this kind wherein the lipstick holder is retained in a separate compartment external to the body of the case will be very serviceable and convenient in practical use.

When it is desired to use the face powder, the case is opened by pressing the finger piece 17 inwardly, thus releasing the latch. The lid or cover can then be raised to a vertically upright position. In this movement of the cover, the member 24 with the lipstick holder therein together with the covering material surrounding said member will assume a slightly angular position relative to the body of the case as indicated in dotted lines in Fig. 3 of the drawings. This obviates the formation of a pronounced crease or crack in the covering material at the hinge line 20 which would otherwise result from the frequent opening of the cover, if the member 24 was rigidly and permanently attached to the back flange 7 of the case frame. Such cracking of the covering material would of course, 25 greatly detract from the ornamental appearance of the article.

I have herein referred to a construction of my new vanity case, which I have found to be very desirable and entirely practical for the purpose in view, and it will be evident that since the several parts thereof are of simple mechanical form, the device may be manufactured on a quantity production basis at relatively small cost. I have disclosed one preferred form of my improved vanity case, but it will nevertheless be understood that the essential features thereof might also be incorporated in various other alternative structures, and I accordingly reserve the privilege of resorting to all such legitimate changes therein as may be fairly incorporated within the spirit and scope of the invention as claimed.

I claim:

- 45 1. In a vanity case, a case body and a lid or closure therefor hingedly connected with one of the body walls of the case, a structurally independent tubular member adapted to removably receive a lipstick holder positioned externally of the case and in contact with said body wall thereof, and a flexible covering material for the outer side and the cover of the case and for said tubular member flexibly retaining said member in associated relation with the case body but permitting of its angular movement relative thereto when the cover of the case is opened.
- 50 2. In a vanity case, a case body and a lid or cover therefor hingedly mounted upon one of the body walls, a structurally independent tubular member to removably receive a lipstick holder associated with said case externally thereof and arranged in parallel relation with one of said body walls, 55 and means connected with said member and

with the body and cover of the case to retain the several parts in assembled relation.

3. In a vanity case, a case body and a lid or closure therefor hingedly connected with one of the body walls, a structurally independent tubular member arranged externally of the case and adapted to removably receive a lipstick holder, and a flexible covering material attached to the cover and the side wall of the case body and confining said tubular member in associated relation therewith and in bearing engagement against the body wall of the case upon which the cover is hinged.

4. A vanity case in the form of a book including a case body having a frame and a side plate therefor, marginal portions of said side plate projecting laterally beyond the frame, a cover hingedly mounted upon one of the frame walls, a tubular member positioned externally of the case in contact with said frame wall, a metal strip secured to one side of said tubular member and of a length equal to the width of said cover and the body plate of the case, and a flexible covering material secured upon the cover and body plates and said metal strip and confining said tubular member closely against the frame of the case body, said tubular member being open at one of its ends and adapted to receive a lipstick holder.

5. In a vanity case, a case body and a lid or cover therefor hingedly mounted upon one end wall of the case body, a rigid member extending transversely of the case in movable contact with the outer face of said end wall, and a single sheet of flexible material covering the outer surfaces of said cover and the side wall of the case body and enveloping said rigid member, said covering material being attached to said member at a point in laterally spaced relation from the cover hinge whereby said member is flexibly connected with the cover for angular movement with respect thereto and in relation to the cover when the latter is opened or closed.

In testimony that I claim the foregoing as my invention, I have signed my name hereto.

DAVID H. ZELL.
